THE RANDALL-FAICHNEY COMPANY, INC., OF BOSTON, MASSACHUSETTS.

CLOSURE OR STOPPER FOR SERUM-CONTAINERS, &c.

1,180,665.

Specification of Letters Patent. Patented Apr. 25, 1916.

Application filed November 29, 1915. Serial No. 63,926.

To all whom it may concern:

Be it known that I, PATRICK J. McELROY, a citizen of the United States, residing at Cambridge, in the county of Middlesex and 5 State of Massachusetts, have invented new and useful Improvements in Closures or Stoppers for Serum-Containers, &c., of which the following is a specification.

This invention relates to a container for 10 storing and injecting serum, the container being provided with a stopper of compressible resilient material, such as rubber or cork, formed as a radially compressible plug and closing its outlet opening, and 15 adapted to receive a cannula through which the serum is ejected by means provided for that purpose.

In some cases the stopper has heretofore 20 been made imperforate, and is punctured by the cannula, the latter being provided with a sharply pointed inner end adapted to puncture the stopper. A cannula is necessarily a slender or attenuated tube so that it is liable to be broken by the force 25 required to drive it through an imperforate stopper formed as a plug and radially compressed by the outlet wall in which it is inserted. Moreover it is not an easy matter to so drive the cannula that it will be centrally located and parallel with the axis of 30 the stopper. There is also liability of clogging the inner end of the lumen of the cannula by material separated from the body of the stopper by the cutting action 35 of the cannula.

In other cases the stopper has been provided with a passage or lumen for the reception of the cannula, said passage being of such form that it is normally open and 40 permits liquid to pass through it when the cannula is not present, the cannula being provided with means whereby the escape of liquid is prevented when the cannula is partly withdrawn from its operative position.

My invention is embodied in an article of manufacture, to wit, a stopper formed as a radially compressible plug having a longitudinal lumen surrounded by the resilient 50 body of the stopper, permitting the easy insertion of a cannula having a blunt inner end, and normally closed and rendered liquid-tight by the resilience of said body,

particularly when the stopper is radially compressed by insertion in the container 55 outlet, the stopper constituting a liquid-tight closure when the cannula is absent.

Of the accompanying drawings forming a part of this specification, Figure 1 represents a longitudinal section of a stopper 60 embodying my invention inserted in the outlet end of a serum container, the cannula being absent; Fig. 2 represents a view similar to Fig. 1, the cannula being present; Fig. 3 represents an enlarged section on line 65 3—3 of Fig. 1; Fig. 4 represents an enlarged section on line 4—4 of Fig. 2; Figs. 5 and 6 represent transverse sections of a stopper showing different forms of lumina; Fig. 7 represents a longitudinal section of a stopper 70 having a lumen extending from the inner end of the stopper partly to the outer end; Fig. 8 represents a sectional view showing the stopper represented by Fig. 7 inserted in a container outlet; Fig. 9 represents 75 a section on line 9—9 of Fig. 7; Fig. 10 represents a section on line 10—10 of Fig. 7.

The same reference characters indicate the same or similar parts in all the views. 80

In the drawings, 12 represents the body and 13 the outlet of a serum container of any suitable form, the container being provided with means (not shown) for ejecting the serum through a cannula inserted in the 85 stopper hereinafter described.

14 represents a stopper or closure made of compressible elastic material such as rubber or cork and formed as a plug to be inserted in the outlet 13 and radially compressed by the wall of said outlet. 90

I form in the stopper 14 a longitudinal lumen 15 which is surrounded by the body of the stopper and is normally closed and rendered liquid-tight by the resilience of 95 said body and is more tightly closed by the radial compression of said body caused by its insertion in the outlet 13, the operation of forming said lumen being one of the steps of the operation of manufacturing the stopper. 100

The lumen preferably has parallel sides normally pressed closely together. The said sides may be curved, as indicated by Figs. 3, 4 and 10. They may however be otherwise formed, as indicated by Figs. 5 and 6,

Fig. 5 showing a lumen which is cruciform in cross section, so that it has more than two abutting sides. Fig. 6 shows a lumen having two abutting sides, said sides being flat 5 instead of curved.

The lumen may be formed in the otherwise completed body of the stopper by a suitably formed elongated cutting instrument sharpened at one end and adapted to form a 10 slit in the stopper without removing material therefrom.

When the stopper is made of moldable material such as rubber the lumen may be formed by inserting a thin strip or blade in 15 the material before it is vulcanized. The blade remaining in the material during the vulcanization and being subsequently removed.

It will now be seen that when a cannula 20 16 having a blunt inner end 17 and a lateral liquid bore 18 communicating with the lumen of the cannula is inserted in the stopper lumen 15, it is enabled by the latter to pass readily through the stopper, the sides 25 of the stopper lumen being pressed closely against the periphery of the cannula and forming a liquid-tight joint therewith. When the cannula is removed the sides of the stopper lumen close together so that no 30 liquid can escape therethrough.

In Figs. 7 and 8 I show a lumen having a normally closed portion 15 characterized as above stated, extending from the inner end of the stopper partly to its outer end, 35 and an enlarged normally open portion 19 extending from the normally closed portion to the outer end of the stopper, and adapted to receive the cannula without being appreciably distended thereby, so that the fric-

tional resistance to the insertion of the cannula is considerably reduced. 40

The stopper is self-sealing, because its lumen is automatically closed or sealed as above described.

The apertured self-sealing stopper constitutes a complete article of manufacture 45 ready for use as an outlet closure and a cannula holder, without change or modification.

Having described my invention, I claim: 50

1. As an article of manufacture, a stopper for serum storing and injecting containers, comprising a body of resilient material having a longitudinal perforation extending therethrough, from end to end, 55 forming a lumen, said perforation being closed throughout its length by the elasticity of the said body, whereby the lumen is self-sealing and liquid tight, said lumen being distensible by a blunt ended cannula inserted 60 in it.

2. As an article of manufacture, a resilient self-sealing apertured closure or stopper formed as a radially compressible plug provided with a longitudinal lumen surrounded 65 by the body of the stopper and including an inner portion extending from the inner end of the stopper partly to its outer end, and adapted to be closed by radial compression of the surrounding portion of the stopper, 70 and an enlarged normally open outer portion extending to the outer end of the stopper, and formed to receive a cannula without being distended thereby, the inner portion being distensible by the cannula. 75

In testimony whereof I have affixed my signature.

PATRICK J. McELROY.
